US0D1077516S

(12) United States Design Patent (10) Patent No.: US D1,077,516 S
(45) Date of Patent: * Jun. 3, 2025

(54) LIQUID DISPENSER

(71) Applicant: Scent Theory Products LLC, New York, NY (US)

(72) Inventors: Kevin Gindi, Brooklyn, NY (US); Ana Angel Rodriguez, Cincinnati, OH (US); Amy Alperin, New Rochelle, NY (US)

(73) Assignee: Scent Theory Products LLC, New York, NY (US)

() Term: 15 Years

(21) Appl. No.: 29/990,521

(22) Filed: Feb. 21, 2025

(51) LOC (15) Cl. 23-08

(52) U.S. Cl.

USPC D6/542

(58) Field of Classification Search

USPC D6/542, 512, 543, 544, 545; D9/297, D9/448, 449, 682, 687, 688, 690, 691,
